CASING FOR AIR FILTERS

Andrew Mazek, Bayville, N. Y., assignor, by mesne assignments, to Pittsburgh Plate Glass Company, a corporation of Pennsylvania

Application August 29, 1952, Serial No. 307,043

3 Claims. (Cl. 183—49)

1

This invention relates to an improved air filter of the type which employs a mass of porous material for the filtering medium.

With air filters of this type the mass of filtering material is ordinarily held in a four-sided open framework of paper chipboard or the like which has a skeletonized network across the two open faces of the framework. In use the pressure of the air flow pushes the downstream side of the framework against its supporting members and this provides an air seal so that the air is forced to pass through the filtering material. In order to achieve an effective air seal, the framework must have dimensional stability. It must be strong enough to withstand shipment and handling without distortion and it must also resist warping in the moisture of the air. If the casing is warped or distorted, it cannot be pushed flat against the supporting members and the air bypasses the filtering material.

In carrying out my invention I provide a framework made of reinforced I-beams which are butted together in the framework to give an extremely light but rigid structure which has proven strong enough in use to withstand shipment and handling without distortion. My I-beams show no appreciable warping throughout the useful life of the filtering medium and as a result the filter framework gives a highly effective air seal with its supporting members.

Further advantages of my invention may be readily understood by reference to the accompanying drawings in which Fig. 1 shows a plan view of my improved air filter casing; Fig. 2 is a side view of Fig. 1 with a portion of the casing cut away to show the filtering medium; Fig. 3 is an isometric view of a corner of the casing which illustrates its construction; Figs. 4, 5, 6 and 7 show blanks of material such as paper chipboard or the like which may be used for making my reinforced I-beams; Figs. 8, 9 and 10 show modifications in the construction of my air filter; and Fig. 11 shows a modified form of I-beam.

In the drawings the numeral 10 indicates an air filter made in accordance with the present invention. As shown, the framework or casing is made of reinforced I-beams 12 which in turn are made from the blanks of Fig. 4. This is done by cutting the material to the form shown after which both sides of the material are folded along the lines of scoring 14 and the top section on each side is folded downwardly along the lines of scoring 16. The I-beam so produced (Fig. 3) is reinforced by the double thickness of material running across approximately one half of the width

2

of the cross flanges 18 and this double thickness also provides a pocket 20 which receives the cross flanges of the adjoining I-beam. A section is cut out of each end portion of the web 22 as indicated at 24 so that the beams may be butted against each other in the finished casing. The I-beams are assembled in the casing as shown in Figs. 1, 2 and 3.

After three of the beams have been assembled 10 a skeletonized wire network 26 is inserted into pockets 20 across the open face on each side of the casing and a section of the filtering medium 27 is inserted between the wire networks. As shown in the drawings I prefer to use a fluffy 15 mass of glass fibers as the filtering medium but any other bulky filtering medium may be used such as an open work mass of plastic fibers or the like. The fourth I-beam is then placed in position to complete the casing. If desired a center support 28 may be positioned across the wire network to reinforce it.

Any convenient means such as a suitable liquid adhesive, gummed tape, staples, or rivets may be used for holding the wire network in pockets 25 20 and the I-beams in position in the casing. However, for maximum strength I prefer to use a liquid adhesive which is applied in a continuous line along the inside of each pocket 20 and on the unexposed portions of flange 18 as indicated at 30 30. Since the grain in adjacent layers of material is crossed the I-beams of my construction are extremely rigid and they show great resistance toward bending in any direction. Pockets 20 provide a firm anchorage for wire network 26 35 and as a result the wire assists in maintaining the sides of the framework in parallel relationship which is extremely important for industrial use where the individual filters are fitted together in a bank.

40 In the preferred form of my invention shown, web 22 of the I-beams is positioned approximately at the center line along the length of cross flanges 18 in order to give the cross flanges maximum support against the thrust of the air stream. 45 It will also be noted that for a given size filter casing this reduces the size of the enclosure so that less filtering material may be used to fill the casing.

Figs. 8, 9 and 10 show modified forms of air 50 filters made from the blanks shown in Figs. 5, 6 and 7. The I-beams are made from the blanks shown in these figures in the same way as above described for the blanks shown in Fig. 4. The air filter casing shown in Fig. 8 is assembled by using 55 two of the I-beams made with the blank of Fig.

4 and two made with the blank of Fig. 5. The advantage of this construction is that the center flanges 22 of the I-beams of Fig. 5 extend out to the edge of the casing and this reinforces the corner which is important for industrial installations where the air filters are held in bank by spring clips at each corner. The same type of construction is shown in Fig. 9 except that I-beams made with the material of Fig. 6 are used in place of the I-beams of Fig. 5. In this construction end flap 32 of the center web is positioned outwardly at a diagonal across the corner of the casing. As shown in Fig. 10 the casing may be assembled with four of the I-beams made of the material of Fig. 6. When this is done one end flap 32 may be extended diagonally under the corner of the casing and the other folded inwardly along the surface of the center flange of the adjoining I-beam. This construction is used where an air filter with especially strong corners is needed. The material shown in Fig. 7 is used where an I-beam having a strong center flange is required. The blank shown in Fig. 7 is folded along the lines of scoring as described above to make one-half of the I-beam of Fig. 11. As shown, the center web 22 is made by overlapping sections of the material and these sections may be laminated together with a suitable adhesive, staples or the like. Of course the end portion of the center web of the I-beam of Fig. 12 may be cut as shown in Figs. 4 and 6 to make the filter casings of Figs. 9, 10 and 11. I have mentioned the use of paper chipboard as a material of construction, but other suitable materials such as resin bonded chipboard paper, impregnated plywood or light gauge metals may also be used.

It will be understood that it is intended to cover all changes and modifications of the examples of the invention herein chosen for the purpose of illustration which do not constitute departures from the spirit and scope of the invention.

What I claim is:

1. In combination with air filtering material, an air filter casing for said material comprising a four-sided open framework having sides of reinforced I-beams which are butted against each other in the framework to give a light but rigid structure having two open faces and a skeletonized wire network positioned across each of said open faces in which each I-beam comprises a center web having a pair of oppositely disposed cross-flanges positioned along the top and bottom edges thereof which extend outwardly from the exterior surface of the web at an angle of approximately 90° and which are doubled back on themselves

55

and extended inwardly beyond the interior surface of the web to increase the strength of the flange and prevent it from warping during use and to form a longitudinal pocket opening into the interior of the casing which contains an edge portion of one of said wire networks, two of said I-beams having cross-flanges which are extended in a longitudinal direction out beyond each end edge of the web, which longitudinally extended end portions are positioned in the pocket of the remaining two adjacent I-beams in the assembled casing in an abutting relationship to give the casing rigidity and dimensional stability.

2. A structure as specified in claim 1 in which the end portion of the web of the remaining two adjacent I-beams is detached from said cross-flanges to form a flap at either end of the said I-beams which extends diagonally out to the corner of the casing and reinforces it.

3. In combination with air filtering material, an air filter casing for said material comprising a four-sided open framework having sides of reinforced I-beams which are butted against each other in the framework to give a light but rigid

25 structure having two open faces and a skeletonized wire network positioned across each of said open faces, in which each I-beam comprises a center web having a pair of oppositely disposed cross-flanges positioned along the top and bottom edges thereof which extend outwardly from the exterior surface of the web at an angle of approximately 90° and which are doubled back on themselves and extended inwardly beyond the interior surface of the web to increase the strength of the flange and guard against warping during use and to form a longitudinal pocket on the interior of the casing which contains an edge portion of one of said wire networks and said cross-flanges being extended in a longitudinal direction beyond each

30 35 40 45 end edge of the web to form a pocket beyond such end edges, said longitudinally extended end portions of two of said cross-flanges being positioned in the pocket formed by the corresponding longitudinally extended end portion of the remaining two adjacent I-beams, in an abutting relationship to give the casing rigidity and dimensional stability.
